(57) **CLAIM**

An ornamental design for a planter set, as shown and described.

DESCRIPTION

FIG. 1 is a perspective view of a planter set embodying the new design, each planter being the mirror image of the other; FIG. 2 is top plan view thereof;

FIG. 3 is a front elevational view thereof;

FIG. 4 is a left elevational view thereof;

FIG. 5 is a right elevational view thereof;

FIG. 6 is a bottom plan view thereof; and,

FIG. 7 is a rear elevational view thereof.

The broken lines are included for the purpose of illustrating portions of the planter set and form no part of the claimed design.

1 Claim, 4 Drawing Sheets(56)
